(57) CLAIM

I claim the ornamental design for a hairstylist utility belt holster, as shown and described.

DESCRIPTION

FIG. 1 is a front and right side perspective view of a hairstylist utility belt holster showing my new design in use; FIG. 2 is a front and right side perspective view thereof; FIG. 3 is a front elevational view of FIG. 2, illustrated with a belt portion in a flat configuration; FIG. 4 is a rear elevational view of FIG. 3; FIG. 5 is a left-side elevational view of FIG. 3; FIG. 6 is a right-side elevational view of FIG. 3; FIG. 7 is a top plan view of FIG. 3; FIG. 8 is a bottom plan view of FIG. 3; FIG. 9 is an exploded perspective view thereof; FIG. 10 is an exploded front elevational view thereof; FIG. 11 is an exploded rear elevational view thereof; FIG. 12 is an exploded left-side elevational view thereof; FIG. 13 is an exploded right-side elevational view thereof; FIG. 14 is an exploded top plan view thereof; and, FIG. 15 is an exploded bottom plan view thereof.

The broken lines showing a person and hair care supplies in FIG. 1 depict environmental matter and form no part of the claimed design. The dot-dash broken lines in FIGS. 7 and 14 depict portions of the hairstylist utility belt holster that form no part of the claimed design. The remaining broken lines represent stitching, and are part of the claimed design.
